CLAIM

The ornamental design for a combined bell and champagne glass, as shown and described.

DESCRIPTION

FIG. 1 is a bottom perspective view of my new design for a combined bell and champagne glass, shown with bell clapper suspended;

FIG. 2 is a front elevation view thereof;

FIG. 3 is a back elevation view thereof;

FIG. 4 is a right side elevation view thereof;

FIG. 5 is a left side elevation view thereof;

FIG. 6 is a bottom plan view thereof;

FIG. 7 is a top plan view thereof; and,

FIG. 8 is another perspective view thereof, shown with bell clapper in a resting configuration.

The broken lines depict portions of the combined bell and champagne glass that form no part of the claimed design.

1 Claim, 5 Drawing Sheets
